CLAIM

The ornamental design for a pager, as shown and described.

DESCRIPTION

FIG. 1 is a perspective view of a pager showing our new design;

FIG. 2 is a top view thereof;

FIG. 3 is a front view thereof;

FIG. 4 is a right side view thereof;

FIG. 5 is a left side view thereof;

FIG. 6 is a back view thereof;

FIG. 7 is a bottom view thereof; and,

FIG. 8 is a top view of an alternative embodiment of the present invention.

The remaining views of the second embodiment are the same as the first embodiment, except for the button details.
